MANIFOLDING RIBBON MECHANISM

George F. Morris, Etobicoke, Ontario, Canada, assignor to International Business Machines Corporation, New York, N. Y., a corporation of New York

Application July 29, 1947, Serial No. 764,447

7 Claims. (Cl. 197—153)

1

This invention relates to typewriting machines and in particular to ribbon feeding and reversing mechanisms.

The primary object is to provide a simple and improved ribbon reversing mechanism.

Another object is to provide a ribbon mechanism suitable for use in making manifold copies.

Another object is to provide an improved manifold copy device for mounting on the carriage of a typewriting machine.

An object is to provide a manifold ribbon feeding mechanism which is relatively simpler in construction and lighter than prior ribbon mechanisms.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view of the carriage of a typewriting machine showing the present invention attached thereto.

Fig. 2 is a front elevation.

Fig. 3 is a perspective view of the carriage.

Fig. 4 is a vertical section on the line 4—4 in Fig. 2.

Fig. 5 is a vertical section on the line 5—5 in Fig. 2.

Fig. 6 is a large scale side view of the feed pawls and ratchets.

Fig. 7 is a vertical section on the line 7—7 in Fig. 6.

Fig. 8 is a view similar to Fig. 6 of a modified form of reversing mechanism.

Fig. 9 is a vertical section on the line 9—9 in Fig. 8.

Fig. 10 is a large scale vertical section on the line 10—10 in Fig. 2.

The invention is shown as applied to the carriage of the well known "Electromatic" electric power-operated typewriter. It will be understood, however, that this has been done purely for convenience in illustrating the invention and that the ribbon mechanism may be applied to other typewriters whether manual or power operated or to other carriages, such as accounting machine carriages with only minor alterations not involving a change in the principle of the invention.

The reference numeral 10 in Fig. 3 generally designates the typewriter of which only a small portion of the framework is shown and which includes the usual type guide 11 and ordinary

inking ribbon 12, the latter being supported by the usual ribbon vibrator 13 and ribbon guides 14. The carriage of the typewriting machine comprises the side plates 15 (Figs. 1 to 4) which are rigidly joined together in a well known way and mounted on the usual track (not shown) so as to be capable of movement to right and left (Figs. 1 and 2). Rotatably mounted in the side plates 15 is the usual platen assembly 16 including the line space ratchet 17 and the platen 18 rotating knobs 19 and this assembly is removably mounted in open notches 15a in the plates 15 and held therein by the usual spring pressed latches 19.

Secured to the carriage side plates 15 are the supporting plates 20 (Figs. 1 to 4) which are roughly triangular in shape. The right hand plate 20 has secured thereto an offset bracket 21 which, together with the left hand plate 20, 20 rotatably supports a shaft 22 on which is loosely mounted the left hand ribbon spool 23, a suitable collar 24 preventing the spool 23 from sliding to the right (Figs. 1 and 2) on the shaft 22. The right hand end of the shaft 22 is received in a flanged bushing 25 (Figs. 2 and 10) which is rotatable in the bracket 21 and retained therein by a collar 26, the set screw of which passes through the bushing 25 and engages the shaft 22. The bore of the bushing 25 loosely receives the end of a thumb screw 27 having a threaded shoulder 27a screwed into a hole in the right hand plate 20. On the shank of this thumb screw 27 the right hand ribbon spool 28 is freely rotatable. It will be seen that the thumb screw 27 may be unscrewed and removed, thereby permitting the ribbon spool 28 to be removed from the machine.

In order to establish a driving connection between the shaft 22 and the spool 28 the flange 40 25 is provided with two diametrically opposite pins 25a which register with holes in the side flange of the ribbon spool 28. Sufficient clearance is provided between the plate 20 and the bracket 21 to permit the ribbon spool 28 to be 45 disengaged from the pins by a lateral movement to the right (Fig. 1) after removal of thumb screw 27.

The feeding of the ribbon and the reversal of the feeding movement is accomplished by means 50 of mechanism which is mounted between the left hand ribbon spool 23 and the left hand plate 20. This mechanism includes the feed ratchet 29 (Figs. 1 to 4, 6, and 7) which is fixed to the left side of the spool 23 and conveniently has eighteen 55 teeth and a similar ratchet 30 fixed to the left

hand end of the shaft 22 adjacent the left hand plate 20. Loosely mounted on the shaft 22 is a hub 31 (Figs. 5, 6 and 7) having two oppositely facing shoulders 31a on which are mounted the control ratchets 32, 33, each of which has ten teeth, these ratchets being secured to the hub 31 by means of the screws 31b of which three are provided for each ratchet in staggered relation, whereby the hub 31 and the two ratchets 32, 33 form an integral unit loose on shaft 22.

Loosely rotatable on the periphery of the hub 31, between the ratchets 32, 33 (Figs. 1 to 7), is a clutch arm 34 which is provided with a slot 34a (Fig. 5) within which is loosely mounted a clutch ball or roller 34b engaging the periphery of hub 31. The slot 34a becomes progressively shallower from the top to bottom (Fig. 5) so that when the clutch arm 34 is rotated counterclockwise in Fig. 5 the wall of the slot, assisted by a spring 34c, tends to jam the ball or roller 34b against the hub 31, thereby enabling the clutch arm 34 to rotate the hub 31 and ratchets 29, 30 as a unit. With the opposite movement of the arm 34, however, the ball or roller 34b tends to roll into the larger space at the top of the slot 34a and permits the arm 34 to move idly. It is apparent that oscillation of the arm 34 between fixed limits will result in the ratchets 31, 32 being progressively advanced in a counterclockwise direction.

Pivotedly mounted on opposite sides of the arm 34 are the feed pawls 35, 36 (Figs. 1 to 6) which are interconnected at their ends by a yoke shaped clip 37 (Fig. 1) loosely received in holes in the noses of the pawls and serving as an anchor for a common operating spring 38 for the pawls, the other end of the spring being anchored to a hook 39 secured to the edge of the clutch arm 34. The spring 38 tends to engage the pawl 35 with ratchets 29 and 32 and the pawl 36 with the ratchets 30 and 33, respectively, the pawls being wide enough for this purpose.

The teeth on the ratchets 32, 33 are staggered so that each tooth on one is aligned axially of shaft 22 with approximately the middle of a tooth space on the other ratchet so that in side view the two ratchets look like a single 20-tooth ratchet.

The ratchets 32, 33 are slightly larger in diameter than the ratchets 29, 30, whereby it is possible for the ratchets 32, 33 to hold the pawls 35, 36 clear of their associated ratchets 29, 30 under certain conditions. The pawls 35, 36 are selectively controlled by the ratchets 32, 33 through a pair of ribbon feelers 40, 41 (Figs. 1 to 4) associated with the ribbon spools 23 and 28, respectively. The feeler 41 is secured to a shaft 42 which is rotatable in the plates 20 and secured to the shaft 42, at its left hand end, is a ratchet control finger 43. The feeler lever 40 is secured to a sleeve 44 to which is attached a similar finger 45. The feeler levers 40, 41 extend rearwardly of the machine and normally ride upon the coils of ribbon on the spools 23, 28, whereby the levers 40, 41 are lifted by the accumulations of ribbon or allowed to drop by the unwinding of ribbon by the respective spools, the levers being weighted at their ends for this purpose. The control finger 43 is adapted to engage the teeth of the ratchet 32 and the finger 45 to engage the ratchet 33 under certain conditions to prevent retrograde movement thereof.

In order to understand the operation of the mechanism just described it will be assumed that a reversal in the ribbon feeding mechanism has just taken place and that the left hand spool 23,

is about to commence winding as illustrated by Fig. 3 in which the right hand spool 28 is full.

Figs. 4, 5, and 6 illustrate the condition of the various ratchets and pawls immediately after the reversal has taken place and the mechanism has become operative to feed the ribbon on the left hand spool 23. It will be noted from these figures that the ratchet 32 is in such a position as to enable the pawl 35 to engage the teeth of ratchet 29 whereas the opposite condition prevails with respect to the ratchet 30, owing to the fact that the teeth in the ratchets 32 and 33 are staggered, the pawl 36 being held out of engagement with the ratchet 30. It will be noted in Fig. 5 that the finger 45, which is attached to the feeler finger 40 for the left hand spool 23, is in the path of movement of a tooth on the ratchet 32.

Let it be assumed that the arm 34 is now oscillated in a clockwise direction and restored an angular distance slightly greater than the angular distance between two teeth in the ratchet 29. This allows the pawl 35 to engage the next succeeding tooth in a clockwise direction on ratchet 29 and, on the return stroke of the arm 34, said ratchet and the spool 23 to which it is attached will be rotated in a counterclockwise direction one tooth space, thereby feeding a small amount of the ribbon on the spool 23.

When the arm 34 is oscillated clockwise the ratchets 32 and 33 follow the arm 34. This is due to the combined effect of friction between the hub 31 and arm 34; the friction between the clutch roller 34b, the hub 31, and arm 34; and the drag of the pawls 35, 36 on the ratchets 32, 33. However, no relative displacement occurs between the arm 34 and the ratchets 32 and 33 with the result that the pawl 36 is maintained in an elevated position clear of the teeth in the ratchet 30 so that on the return stroke of the arm 34 the ratchet 30 is not affected.

While the finger 45 is in the path of a tooth in the ratchet 32 there will exist a clearance between such tooth and the end of the finger of approximately the angular distance between two teeth on the ratchet 29 with the result that the tooth merely moves up to the finger 45 and may move the ratchets 32, 33 relative to the arm 34 an insignificant amount insufficient to disturb the relation between the pawl 36 and the ratchet 30. Thus with each oscillation of the arm 34 the ribbon is fed on to the spool 23 and as this action continues the finger 45 is gradually moved in a clockwise direction until it is completely clear of the ratchet 32. While this action is taking place the other finger 43 will be gradually permitted to drop, due to the unwinding of the ribbon from the spool 23.

When the arm 34 is fully restored as in Figs. 4, 5, and 6, with the parts operating under the above conditions, there will be a tooth in ratchet 33 just clear of the arc traversed by the end of the finger 43 and this tooth, as the arm 34 is rocked clockwise, will travel across such arc and clockwise a distance equal to slightly more than the distance between two teeth on the ratchet 30 but, owing to the fact that the finger 43 is, at this time, quite a ways away from the ratchet 30, nothing will happen to change the relation between the ratchets 32, 33 and the pawls 35, 36 and the ribbon will continue to feed on the spool 23.

Ultimately the spool 28 will become exhausted and there will be a point where the finger 43 will drop into a position to catch the tooth of ratchet 33 mentioned above and will assume a position like the finger 45 in Fig. 4. It is quite

clear, that with the ratchet 33 in the position of Fig. 4 and with the finger 43 now occupying the position occupied by the finger 45 in Fig. 4, the next oscillation of the arm 34 will cause the finger 43 to catch a tooth in the ratchet 33 and prevent said ratchet, and likewise the ratchet 32, from moving clockwise with the arm 34. Thus there will be effected a displacement of the ratchets 32, 33 in a counterclockwise direction relative to arm 34 and this will cause the tooth which is holding the pawl 36 out of engagement with ratchet 30 to move out from under said pawl and permit it to engage the ratchet 30. At the same time a tooth of ratchet 32 will move underneath the pawl 35 and elevate it out of engagement with the ratchet 29.

With the restoring movement of the arm 34 the tooth which engaged the finger 43 will be backed away from the finger 43 and the same relationship will now exist between the finger 43 and the ratchet 33 as exists in Fig. 5 between the finger 45 and the ratchet 32. Since the pawl 36 now engages ratchet 30, the latter will be actuated a tooth space in a counterclockwise direction upon the return of the arm, since the shifting movement which effects the reversal in the feed of the ribbon takes place during the clockwise portion of the oscillation of arm 34. It is thus apparent that there is no risk of locking or jamming the two pawls 35, 36, due to indefinite transition as sometimes happens with other feeding mechanisms.

Owing to the spacing of the teeth in the ratchets 32, 33, it is impossible for both pawls 35 and 36 to engage their respective ratchets 29 and 30 simultaneously. Since the reversal takes place on the forward clockwise stroke of the arm 34, the ribbon is moved backwardly instead of forwardly at the time of reversal so that the next impression of the type will not be through the same portion of the ribbon. It is thus seen that the point reversal of the ribbon is clear-cut and sharp and there is no chance that several impressions may be made through the same portion of the ribbon during the reversal period as sometimes happens with ribbon mechanisms in which tension is relied upon to effect reversal and movement of the ribbon is blocked until enough tension can be built up in the ribbon to render the reversing mechanism effective.

In Figs. 8 and 9 there is shown a modified form of control mechanism for effecting the reversal of the ribbon. In place of the ratchets 32 and 33 there is provided a pair of cam plates 50, 51, having cam lobes 50a, 51a, respectively designed to cooperate with the pawls 52, 53. The cams 50, 51 are pivotally mounted on an arm 54 by means of shouldered washers 55 secured to the arm 54 by means of screws 56a, the arm 54 and the washers 55 being centered on the shaft 22 by a bushing 56. The cams 50, 51 are formed with shallow depressions 50b, 51b receiving the balls 57 of a double ball catch carried by a hole in the arm 54, a spring 58 common to both balls urging them into the depressions 50b, 51b. Each cam has two depressions enabling it to be yieldingly held in either of two set positions. The cams 50, 51 are interconnected by a pair of intermeshing pinions 59 which are pivoted on studs carried by the arm 54. The arm 54 is bored to accommodate the pinions 59 and these bores intersect to provide a space to permit the intermeshing of the pinions 59. Each pinion meshes with suitable teeth formed in one of the cams 50, 51 and the effect of this construction is to

compel the cams to move in scissors fashion whenever either one of them is given a displacement. The cams 50, 51 are each provided with a single tooth designated 50c, 51c (Fig. 8), designed to cooperate with the fingers 45 and 43, respectively.

It will be noted in Fig. 8 that the parts are shown in the same operating condition as the parts in Fig. 4, it being assumed that the finger 45 has just been effective to reverse the ribbon to cause it to feed on the left hand spool 23 as was assumed above in describing the operation of the mechanism disclosed in Figs. 4 to 7. It will be noted that, as in Fig. 4, the finger 43 will not be in a position to engage the tooth 51c and that the tooth 50c is displaced away from the end of the finger 45 approximately one tooth space on the ratchet 29 whereby, when the arm 54 is oscillated clockwise, the tooth 50c will move up to engage the finger 45 at about the end of the stroke of the arm 54 and will have no effect on the relative positions of the cams 51, 50.

In Fig. 8 the cam lobe 51a is engaging the pawl 53 and holding it out of engagement with the ratchet 30 whereas the lobe 50a is clear of the pawl 52, permitting the pawl 52 to drive the ratchet 29. When the positions of the fingers 43, 45 are reversed, as will take place when the right hand spool 28 becomes exhausted, the finger 43 will take the position now shown by the finger 45 in Fig. 8 and catch the tooth 51c, thereby preventing the cam 51 from following the arm 54. This causes the cam 51 to be displaced in a counterclockwise direction relative to the arm 54 withdrawing the lobe 51a from underneath the pawl 53 and actuating the cam 50 in a clockwise direction relative to the arm 54, through pinions 59, to move the lobe 50a underneath the pawl 52 and elevate the latter out of engagement with the ratchet 29.

In order to limit the scissors-like motion of the cams 50, 51 on the arm 54 to a distance equivalent to approximately a tooth space on the ratchets 29, 30, there is provided a stop pin 54a.

The arm 34 may be actuated by any suitable means such as a line space lever mounted on the carriage. In the illustrative embodiment of the invention it is preferred to connect the arm 34 by a link 60 to the usual line space slide 61 which is vertically guided and actuated, in the manner disclosed in Patent 1,957,322, each time the platen 16 is line-spaced. The slide 61 carries a line space pawl 62 which coacts with the line space ratchet as in said patent.

The usual line space control lever is replaced by an L-shaped lever 63 which may be reached from the rear of the machine. This lever carries the usual pin 63a which functions in the usual way with a second lever 64 to control the stroke of the pawl 62.

In order to prevent the ribbon spools 23, 28 from spinning when they are unwinding, the brake fingers 70 are provided. These fingers are pivotally mounted on the studs 71 (Figs. 1, 3, and 4) and spring-urged into engagement with the edges of the spools 23, 28 by means of springs 72, the fingers 70 being provided with suitable pads of material, such as leather. Preferably, the brake fingers are wide enough to engage the edges of both spool flanges in each case.

For the purpose of guiding the manifolding ribbon R across the writing line there is provided the ribbon guide bar 75 (Figs. 1 to 4) which is attached to the side arms 76 by means of the knurled thumb screws 77. Secured to the ends of the bar 75 are the ribbon guide frames 78 in

which are mounted the 45° ribbon guide rollers 19 and the vertical ribbon guide rollers 20. The ribbon R is led from the right-hand spool 28 forwardly and downwardly around the right-hand 45° roller 19, thence crosswise of the machine between the first two plies of the manifold forms, then around the left-hand vertical roller 20 back to the right between the second and third plies of the forms, around the right-hand roller 20, thence back to the left between the third and fourth plies, around the left-hand 45° roller 19, and thence on the ribbon spool 23. This allows three working stretches of the ribbon for the purpose of making three copies besides the copy made with the main ink ribbon 12 as shown in Fig. 3.

For the purpose of guiding the manifold stationery to the ribbons there is provided a series of adjustable guides generally designated 31 (Figs. 1 to 3), designed to accommodate several different widths of work sheet, whereby the pack of manifold stationery may be made up of strips of different widths. This guiding means is adjustably mounted on the paper table 22 which is mounted in the usual way on the studs 21. Any suitable guiding means may be used.

The side arms 16 are pivotally mounted at 83 (Figs. 1 and 3) in the plates 20, each of which is provided with an offset lug 20a supporting the adjacent side arm 16 and engaged by a sprung urged latch 84 pivoted on the adjacent side arm 16. The latches 84 may be released to raise the assembly including the bar 15 and the side arms 16 to carry the ribbon R up from between the plies of stationery to facilitate the insertion of forms.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A ribbon mechanism comprising a pair of feed ratchets; pawls, one for each ratchet, for imparting rotation to said ratchets; a pair of 50 control members, one for each ratchet and its associated pawl, said control members having projections coacting with said pawls and capable of holding said pawls out of driving relation to said ratchets; means interconnecting said members including a differential gear arranged so that movement of either member to move the related pawl out of driving relation with its ratchet at the same time causes the other member to move to a position permitting the other pawl to have driving engagement with its ratchet; and ribbon controlled means for selectively moving said control members in alternation.

2. A ribbon mechanism comprising a pair of feed ratchets; feed pawls, one for each of said ratchets; a pair of control elements each rotatably mounted adjacent one of said pawls and movable to alternate positions in which the adjacent pawl is engaged with and disengaged from its associated ratchet, respectively; means including a reversing gear train interconnecting said elements whereby rotation of either element to one alternate position to engage its pawl with the associated ratchet compels the other element

to move to the other alternate position to disengage the pawl for said other element from the ratchet for said other element, means for actuating said pawls in unison, and ribbon controlled means for causing the actuating means to move said elements to their alternate positions to thereby effect a reversal of the ribbon.

3. In combination with the carriage and platen of a typewriting machine, a cross shaft 10 mounted in said carriage parallel with said platen, a pair of ribbon spools at the ends of said platen and coaxial with said shaft, one of said spools being keyed to the end of said shaft, means to support and guide a ribbon between said spools and along the writing line on the platen; a pair of feed ratchets, one fixed to said shaft adjacent the loose spool and the other secured to the loose spool a spaced distance from the ratchet fixed to said shaft; a rock arm journaled on said shaft between said ratchets, a pair of feed pawls carried by said arm and coacting with said ratchets, means to oscillate said arm; a pair of pawl control members journaled on said shaft, one on each side of said arm adjacent one of said ratchets, each of said control members being shaped to alternately engage and disengage the pawl for the adjacent ratchet from said ratchet in two alternate movements; means interconnecting said control members whereby, when 25 either one moves to a position to engage its pawl with the associated ratchet, the other control member will be moved to disengage the remaining pawl from its ratchet; means to cause said control members to oscillate with said arm, and means to sense exhaustion of the ribbon from said spools and including elements engageable with said control members, when a spool becomes exhausted, to enable an oscillation of said arm to move the control member for the exhausted spool to pawl engaging position.

4. The invention set forth in claim 3 in which the control members comprise a pair of ratchets and the interconnecting means maintains the teeth of said ratchets in a staggered relation.

5. The invention set forth in claim 3 in which the control members comprise a pair of cams and the interconnecting means comprises differential gearing.

6. A ribbon feed mechanism comprising a pair of ribbon spools, means for feeding said spools including a pair of ratchet and pawl devices, one for each spool; means for actuating the pawls of said ratchet and pawl devices including an oscillatable arm carrying the pawls of said devices; a pair of control members, one for each pawl, each member movable from a pawl engaging to a pawl disengaging position, means interconnecting said members whereby movement of either member to pawl engaging position causes the other member to move to pawl disengaging position, means normally compelling said members to move with said arm in its pawl driving movements, whereby said members maintain the engaged pawl in engaged position and the disengaged pawl in disengaged position, and means to detect exhaustion of said ribbon spools, including arresting means operative when either ribbon spool becomes exhausted to engage the control member for the exhausted spool and prevent said member from moving with said arm to thereby effect shifting of such member to pawl engaging position and the other member to pawl disengaging position.

7. The invention set forth in claim 6 in which the control members comprise a pair of cams and

the interconnecting means comprises means to cause said cams to move in opposite directions when either one is engaged by the arresting means.
